UNITED STATES PATENT OFFICE.

THOMAS CORSCADEN, OF NEW BRITAIN, CONNECTICUT, ASSIGNOR TO THE AMERICAN PULLEY COMPANY, OF PHILADELPHIA, PENNSYLVANIA.

DESIGN FOR A HUB-CLAMP FOR PULLEYS.

SPECIFICATION forming part of Design No. 27,248, dated June 22, 1897.

Application filed May 8, 1897. Serial No. 635,747. Term of patent 14 years.

To all whom it may concern:

Be it known that I, THOMAS CORSCADEN, a citizen of the United States, residing at New Britain, in the county of Hartford and State 5 of Connecticut, have invented and produced a new and original Design for a Hub-Clamp for Pulleys, of which the following is a specification, reference being had to the accompanying drawings, in which—

10 Figure 1 is a side elevation of a hub-clamp for pulleys, showing my design; and Fig. 2 is an end view of the same.

The leading or material feature of my design consists of a pulley-clamp having the 15 contour in side view and end view substantially as herein shown. In side view my pulley shows a semicircular recess A on its inner edge, with a middle top portion 3, which is concentric thereto, while the top at each end 20 of said middle portion 3 is straight and flat,

as at 4 4, and parallel to the inner edges 5 by the sides of the semicircular recess A. The contour at the ends of this clamp, as seen in side view, extends downwardly a short distance at right angles to the top 4, as at 6, and 25 from there slants inwardly, as at 7, to the edge 5, the junction of said edges 5 and 7 being slightly rounded. The ends 6 and 7 show in end view substantially the form of a flattened and inverted U, as shown in Fig. 2, 30 and the concentric middle portion 3 is seen rising above the top 4, as shown in said Fig. 2.

What I claim as new, and desire to secure by Letters Patent, is—

The design for a pulley hub-clamp, substantially as herein shown and described.

THOMAS CORSCADEN.
